Patented Nov. 11, 1924.

UNITED STATES PATENT OFFICE.

ALBERT F. H. SEELIG, OF ST. LOUIS, MISSOURI.

ENAMELING FURNACE.

Application filed April 12, 1922. Serial No. 551,785.

To all whom it may concern:

Be it known that I, ALBERT F. H. SEELIG, a citizen of the United States, residing in the city of St. Louis and State of Missouri, have invented new and useful Improvements in Enameling Furnaces, of which the following is a specification.

This invention relates to furnaces and while the invention may be employed in the construction of furnaces for any purpose, in the accompanying specification I have described the same as applied to an enameling furnace of the recuperator type.

The general object of the invention is to produce a furnace of this kind having a construction which will operate to extract a relatively large amount of the heat from the hot gases before permitting the same to pass to the stack; to provide improved means for circulating or directing the hot gases through the heating chamber and through or around the walls thereof to reduce the amount of radiation; to provide improved means for heating the incoming air for combustion in the furnace; to provide improved means for regulating and controlling the flow of gases and air through the furnace; and also to provide means for facilitating the examination of the flames or gases passing through the heating flues.

Further objects of the invention will appear hereinafter.

The invention consists in the novel features, and in the general combination of parts to be particularly described herein-after, all of which contribute to produce a simple and efficient enameling furnace. A preferred embodiment of my invention will be particularly described in the following specification, while the broad scope of my invention will be pointed out in the appended claims.

In the drawing,

Figure 1 is a longitudinal vertical section 45 through the enameling furnace;

Figure 2 is a vertical cross section through the furnace taken on the line 2—2 of Figure 1;

Figure 3 is a horizontal section through the furnace taken about on the line 3—3 of Figure 2;

Figure 4 is a vertical section taken on the line 4—4 of Figure 2; and

Figure 5 is a section taken about on the line 5—5 of Figure 3, but this view is fragmentary and broken away.

The furnace includes a fire-box, burner or producer 1 in which producer gas may be formed before passing into the body 2 of the furnace.

Any desired kind of firing may be employed. Where producer gas firing is used a water pipe 3 may be provided delivering to drip-pans 4 just inside the ash door 5 at the back of the furnace. The rear wall 6 of the producer may be provided with an elevated charging door 7. The body of the furnace includes a heating chamber 8 having vertical side walls 9 and having an inner arch 10 on its upper side. Within this heating chamber a muffle 11 is supported, the bottom 12 of the muffle resting upon piers or baffle walls 13 (see Figures 2 and 3). These walls extend parallel with each other so that the space between them is formed into a main combustion chamber 14 which receives the hot gases from the producer as they come over the bridge wall 15. These baffles 13 terminate short of the forward wall 16 of the furnace so that the hot gases can turn 70 at their rear ends 17 and pass toward each side; in this way the hot gases are made to return toward the back of the furnace in re-passes through secondary combustion chambers 18 (see Figures 2 and 3). By this means I direct the hot gases in a plurality of passes directly under the bottom of the muffle and I increase the virtual length of the combustion chamber to such an extent as to insure a very complete combustion taking 80 place under the bottom of the muffle.

The edges of the bottom 12 of the muffle and the side walls of the muffle are supported on buttresses 19 which extend in from the side walls 9 of the heating chamber and these buttresses are carried up to the level of the line 20 under the arch 10 and over the upper side of the arched cover or arch 21 of the muffle. These buttresses 19 are disposed equidistant apart so as to form a 100 plurality of gas flues 22 which direct the gases past the side walls of the muffle. After leaving these gas flues the gases pass into the upper portion of the heating chamber directly under the arch 10.

According to my invention I provide means for receiving the gases from the heating chamber 8 and circulating the same through the side walls of the furnace. In other words I provide the heating chamber 110 with a jacket including vertical side walls 23 which are spaced from the side walls

9 of the heating chamber and which are surmounted by an upper arch or outer arch 24 which overlies the inner arch 10. The arch 24 is, of course, separated from the arch 10 by an arch space 25 which communicates with the side jacket spaces 26 between the walls 9 and 23. I prefer to take the hot gases from the heating chamber 8 through the key-stone 26 of the inner arch, for which purpose this part of the arch is provided with a plurality of openings 27. Through these openings the hot gases pass in the manner indicated by the arrows in Figure 2.

15 I then pass these hot gases through the jacket space. I construct the furnace in such a way that the incoming air for combustion in the furnace is carried through the jacket space 26 and in this way I pre-
20 heat the air so that the furnace will operate as a recuperator furnace. The incoming air is heated methodically, that is to say, while I provide means for passing the hot gases in contact with the air flues, the general direction of flow of the air through the flues is opposite to that of the hot gases. The gases may also pass up from the combustion chamber 14 through openings 14^a, see Figure 1, to come into contact with the
25 head of the muffle.

Furthermore according to my invention I provide means for controlling the flow of air through the air flues and for cutting off at will the flow through the uppermost of these flues. I prefer to provide a pair of vertical header flues 28 (see Figure 3) which are built in the back wall of the furnace body. The air flues 29 are simply parallel conduits set in the jacket space 26 and communicating with each other in series, the air being admitted, through air inlets 30 into the lowest air flues. From this point the air passes toward the front and flows successively through the air flues as indicated by the arrows in Figure 4. In addition to the bottom air inlets 30 each pass or air flue may be provided with its own individual air inlet 31. These air inlets are all closed by removable plugs 32 in the furnace wall which may be provided with dampers if desired. As the air flows through the air flues 29 it becomes heated by the hot gases which pass down through ducts 33 formed between the flues and the vertical walls of the furnace (see Figure 2).

60 I provide means for regulating the flow of the air between the air flues 29. For this purpose, I provide movable gates or slides in the form of loose bricks 34 in the end walls of the furnace. These bricks are in line with the division walls between the air flues and by shoving them in all the way they will cut off the upper flues from the lower ones. All of the air flues 29 at the

rear of the furnace are provided with emergency outlets 35 closed by removable plugs 36 which lead from the air flues directly into the header flues 28. This organization enables me to utilize the dampers 34 to retard the flow of the air to regulate the temperature thereof when delivered at the combustion chamber. Also, if desired, by completely shutting the upper dampers 34 and removing the proper plug or closure 36, the air can be by-passed from the upper air flues and sent directly into the air header 28. Removable stoppers 37 may be employed in the front wall of the furnace for giving access to the front ends of the air flues for observation purposes.

As the hot gases leave the nests of air flues they pass into header flues 38 located at each side of the furnace (see Fig. 2) and the ends of these headers communicate with up-take flues 39 at each side of the furnace (see Fig. 2), and the upper ends of these headers communicate with stack flues 40 built in the cover-wall 41 of the furnace and which lead the hot gases to the stack.

35 In order to regulate the flow of the hot gases as they pass through the jacket the side walls of the furnace are provided with dampers 42 in the form of loose bricks in the wall (see Fig. 2). By shoving these dampers in they will cut off more or less the flow of gases through the up-take flues 39.

40 In order to regulate the flow of the gases from the heating chamber into the jacket the outlets 27 are provided with one or more closures 43 which may be simply blocks of fire-brick resting on the top of the arch. In order to render these block dampers accessible from the exterior I provide removable plugs 44 directly over them in the cover wall 41. By removing the plugs 44 the furnace-man may insert a pinch-bar through the opening and shove the damper blocks 43 into any position desired. I also prefer to mount the plugs 44 in larger removable plates 45, respectively, which may be removed if necessary to remove the damper blocks 43. These plates 45 seat on the key-stone of the arch through which a large opening 46 is formed through which the damper blocks may be inserted.

45 Although the floor of the main combustion chamber 14 is level, I prefer to provide an inclined floor 47 in the secondary combustion chambers 18 (see Figure 5). The inclination of this floor tends to initiate an upward movement of the gases to start the flow through the gas flues 22.

50 After the hot air passes down through the header flues 28 it passes through openings 48 which deliver the hot air over the bridge 15 (see Figure 1).

55 In addition to the side gas flues 22 the

inner end or head 49 of the muffle is provided with gas flues 50 which are directly over the highest point of the inclined floors 47. These inclined floors prevent any possibility of forming a dead pocket under the back end of the muffle.

Similar flues 50^a are located over the openings 14^a.

In order to enable the interior of the muffle to be examined when desired I provide peep holes 51 in the forward wall of the furnace having removable plugs 52.

In order to enable the condition of the gases passing up the vertical gas flues 22 to be inspected I provide peep holes 53 in the forward wall of the furnace which align with a plurality of peep holes 54 which are formed in alignment with each other in the buttresses 19.

The gas flues 50 and 50^a are formed between buttresses 55 which extend vertically across the back end of the muffle.

The forward wall of the furnace is provided with a suitable charging opening 56 with a door 57.

The bottom and side walls of the muffle 11 are preferably constructed of flat tiles with interlocking connections as shown. Preferably the intermediate joints between these tiles in the bottom are located over the baffle walls 13, and the joints at the edges of the bottom are formed over longitudinal sills 58 supported on the buttresses 19.

In constructing the furnace the upper arch 24 may be supported on wooden forms resting on the inner arch and which can be left in place and burnt out when the furnace is put into operation.

What I claim is:

1. In a furnace of the kind described, the combination of a heating chamber, a muffle supported therein, and means for directing the hot gases in a plurality of passes and in opposite directions under and in direct contact with the bottom of the muffle.

2. In a furnace of the kind described, a heating chamber, a muffle supported therein, a fire-pot or burner, means for directing the gases of combustion from the fire-pot into contact with the bottom wall of the muffle, air flues in the side walls of the heating chamber, means for passing air in an upward direction through said flues, means for conducting the combustion gases after contact with the bottom of the muffle upward around the side and top walls of said muffle and then downward into contact with the air flues to heat the air passing upward therethrough, and means for delivering the air from the said flues adjacent the fire-pot to supply air for combustion.

3. In a furnace of the kind described, the combination of a heating chamber, a muffle supported therein, with its walls spaced

from the walls of the heating chamber, a fire-pot or burner, a combustion chamber leading from the fire-pot under the bottom of the muffle, so that the heated gases pass under the bottom of the muffle, means for directing the hot gases in another pass, under the bottom of the muffle, means for conducting hot gases thereafter up the side walls of the muffle, air-flues in the walls of the heating chamber to receive incoming air, means for directing the hot gases into contact with the said air-flues to heat the incoming air, and means for delivering the incoming air adjacent the fire-pot to supply oxygen for combustion.

4. In a furnace of the kind described, the combination of a plurality of substantially parallel air-flues, means for passing hot gases in contact with the walls of the flues to heat the air passing therethrough, a header flue extending transversely to the parallel flues, means operable from the exterior of the furnace for closing off the communication between the parallel flues, said air flues having openings with closures therein, leading from the same into said header flue, and means for rendering the said closures accessible from the exterior of the furnace.

5. In a furnace of the kind described, the combination of a plurality of substantially parallel air-flues connected together in series, so that the air passes through the flues in succession, means for passing hot gases in contact with the walls of the flues to heat the air passing therethrough, a header flue extending transversely to the parallel flues, means operable from the exterior of the furnace for closing off the communication between any of the parallel flues and its adjacent flues, said air-flues having openings with closures therein, leading from the same into said header flue, said furnace having a wall at the ends of the air-flues adjacent the header flue with removable plugs, rendering the said closures accessible from the exterior of the furnace.

6. In a furnace of the kind described, the combination of a plurality of substantially parallel air-flues connected together in series, so that the air passes through the flues in succession, means for passing hot gases in contact with the walls of the flues to heat the air passing therethrough, a header flue extending transversely to the first named flues, gates mounted in the furnace wall at the ends of the air flues and operable from the exterior of the furnace for closing off the communication between any of the parallel flues and its adjacent flues, said air-flues having openings with closures therein leading from the same into said header-flue, and means for rendering said closures accessible from the exterior of the furnace, whereby the air passing through the air-

flues may be delivered at will from any air-flue into the header-flue.

7. In a furnace of the kind described, the combination of a plurality of substantially parallel air-flues connected together in series, so that the air passes through the flues in succession, means for passing hot gases in contact with the walls of the flues to heat the air passing therethrough, a header flue 10 extending transversely to the parallel flues, means operable from the exterior of the furnace for closing off the communication between any of the parallel flues and its adjacent flues, said air-flues having openings with closures therein, leading from the same into said header flue, said furnace having a wall at the ends of the air-flues adjacent the header flue with removable plugs, rendering the said closures accessible from the exterior 20 of the furnace, and removable stoppers in the wall of the furnace adjacent the ends of the parallel flues to enable the air temperature in the different flues to be examined.

8. In a furnace of the kind described, the combination of a plurality of substantially parallel air-flues extending between the end walls of the furnace and connected together in series so that the air passes through the flues in succession, means for passing hot gases in contact with the walls of the flues to heat the air passing therethrough, a header-flue adjacent one of the end walls of the furnace and extending transversely to the parallel flues, means operable from the exterior of the furnace for closing off the communication between the parallel flues, said air flues having openings with closures therein, leading from the same into said header-flue, the end wall adjacent the header-flue having hand-holes with removable plugs therein, accessible from the exterior and rendering the said closures accessible from the exterior of the furnace.

9. In a furnace of the kind described, the combination of a plurality of substantially horizontal and parallel air-flues located in the side walls of the furnace and formed by spaced parallel conduits connected together at their ends in series so that the air passes through the flues in succession, means for passing hot gases transversely through the spaces between the conduits and in contact with the walls of the flues to heat the air passing therethrough, a fire-pot, and means for conducting heated air from the air-flues to the fire-pot to supply oxygen for combustion.

10. In a furnace of the kind described, the combination of a heating chamber, having an inner wall and an inner arch, a muffle supported within the heating chamber, means for passing the heating gases in contact with the outer sides of the wall of the muffle and into the space under the said

inner arch, said inner arch having an outlet opening for the hot gases, means for conducting the hot gases from the outlet in contact with the outer side of the inner walls, air-flues disposed horizontally on the outer side of the inner walls in the path of the heating gases, a fire-pot and means for conducting the air from the air-flues to a point adjacent the fire-pot to supply oxygen for combustion. 75

11. In a furnace of the kind described, the combination of a heating chamber having an arch with an outlet opening therethrough, a muffle within the heating chamber, means for passing the heating gases around the muffle and through said outlet, air flues at the sides of the heating chamber, means for conducting the hot gases from the outlet past the air flues to heat the air within the same, a fire-pot to receive the heated air, a cover wall over the arch having an opening therethrough, and a damper sealing on the arch at said outlet and accessible through the said opening in the cover wall. 80

12. In a furnace of the kind described, the combination of a heating chamber having an inner arch and an upper arch, with an arch-space between the arches, inner walls supporting the inner arch and outer walls supporting the upper arch, a muffle 85 disposed within the heating chamber, means for circulating the hot gases around the muffle, said inner arch having an outlet through which the heating gases may pass into the space between the arches, said upper arch having an opening therethrough, a damper accessible through the opening for regulating the flow of gases through the outlet, air flues disposed between the inner and outer side walls of the furnace, means 90 for conducting the hot gases from the arch space into contact with the air flues to heat the air therein, a fire-pot, and means for conducting the air from the flues into the same to supply oxygen for combustion. 100

13. In a furnace of the kind described, the combination of a fire-pot, a heating chamber receiving the hot gases from the fire-pot, a muffle mounted within the heating chamber, baffle walls under the muffle for conducting the gases from the fire-pot and under the middle portion of the bottom of the muffle, said baffle walls terminating short of the opposite end of the furnace and cooperating with the side walls of the furnace to conduct the hot gases in a return pass located at each side of the furnace, gas flues receiving the gases beyond the return passes and operating to conduct the same upwardly along the outer sides of the muffle, and means for conducting the gases to the furnace outlet. 110

14. In a furnace of the kind described, the combination of a heating chamber having a muffle therein with the walls of the 115

- muffle spaced from the walls of the heating chamber, a jacket wall surrounding the wall of the heating chamber with a jacket space between the walls of the chamber and the 5 jacket, means for circulating hot gases under the muffle and through the space between the muffle wall and the wall of the heating chamber, means for conducting the hot gases from the heating chamber through the jacket 10 space, air flues disposed horizontally in the jacket space and receiving heat from the hot gases, a fire-pot delivering the hot gases to the heating chamber and receiving heated air from the air-flues. 15 15. In a furnace of the kind described, the combination of a fire-pot, a heating chamber receiving the hot gases from the fire-pot, a muffle mounted within the heating chamber, with its walls spaced from the 20 walls of the heating chamber, a jacket wall surrounding the heating chamber with a jacket space between the walls of the jacket and heating chamber, means for directing the hot gases under the muffle and through 25 the space between the walls thereof and the walls of the heating chamber, air-flues disposed horizontally in the jacket space, means for directing the hot gases from the combustion chamber downwardly past the 30 air-flues, to heat the air therein, said furnace having a cover wall with flues therein, receiving the hot gases from the jacket, and means for delivering heated air at a point adjacent the fire-pot. 35 16. In a furnace of the kind described, the combination of a fire-pot, a heating chamber receiving the hot gases from the fire-pot, a muffle mounted within the heating chamber, with its walls spaced from 40 the walls of the heating chamber, a jacket wall surrounding the heating chamber with a jacket space between the walls of the jacket and heating chamber, means for directing the hot gases under the muffle and through 45 the space between the walls thereof and the walls of the heating chamber, air-flues disposed in the jacket space, means for direct- ing the hot gases from the combustion chamber downwardly past the air-flues, to heat the air therein, up-take flues built in the 50 furnace wall receiving the hot gases beyond the air flues and conducting the same upwardly, said furnace having a cover wall with horizontal flues therein to lead the 55 gases from the up-take flues toward the stack. 17. In a furnace of the kind described, the combination of a fire-pot, a heating chamber, a muffle supported therein with its walls spaced from the walls of the heating chamber, said furnace having a main combustion chamber under the middle portion of the muffle receiving the hot gases from the fire-pot, having baffle walls forming the 60 sides thereof, extending away from the fire-pot and terminating short of the opposite wall to permit the gases of combustion to turn their ends, secondary combustion chambers taking the gases from the main combustion chamber, and having bottom walls 65 inclining upwardly in the direction in which the gases pass over them, side gas flues and end gas flues receiving the gases from the said combustion chambers and conducting the same up the side walls and up the end 70 wall of the muffle. 18. In a furnace of the kind described, the combination of a fire-pot, a heating chamber, receiving the gases from the fire-pot, a muffle supported in the heating chamber with its side walls separated from the 75 side walls of the heating chamber, buttresses extending upward between the walls of the muffle and the heating chamber, and forming side gas flues, and means for conducting the hot gases up the said flues, said buttresses and the end wall of the furnace having aligning peep-openings through 80 which the flames in the side flues may be seen. 85 90 In testimony whereof, I have hereunto set my hand.

ALBERT F. H. SEELIG.
